METHOD FOR TREATING OILS

Ulric B. Bray, Palos Verdes Estates, Calif., assignor to Union Oil Company of California, Los Angeles, Calif., a corporation of California

Original application August 1, 1933, Serial No. 683,187. Divided and this application December 14, 1935, Serial No. 54,503

20 Claims. (Cl. 196—13)

This invention relates to a method for separating asphalt and wax from oils containing the same. The invention relates particularly to a method for removing the asphalt from oils containing the same in a plurality of stages. The present invention is a division of Serial No. 683,187, filed August 1st, 1933 now U. S. Patent 2,041,276, which is a continuation, in part, of my co-pending applications Serial No. 466,189, filed July 7th, 1930, and Serial No. 659,855, filed March 6th, 1933 now U. S. Patent No. 2,010,008.

In my co-pending application Serial No. 466,189, filed July 7th, 1930, I disclosed a process for producing lubricating oils and for separating asphalt and/or wax from oils containing the same. In this process a crude oil residuum containing asphalt which was topped so that the residue contained fractions having a viscosity from 400 to 500 seconds Saybolt universal at 100° F. was commingled with a liquefied normally gaseous hydrocarbon solvent such as propane under pressure sufficient to maintain the solvent in the liquid state. This permitted precipitation of asphalt. The solution of lubricating oil in the liquid solvent and precipitated asphalt was permitted to settle in order to stratify the precipitated asphalt from the oil solvent solution. The latter was expanded through heating coils to vaporize the solvent and thus leave behind a lubricating oil substantially free from asphalt. The precipitated asphalt in the decanter was removed as a slurry of propane and bitumen which was also heated to remove residual propane. The propane in each case was recovered by compression and cooling and returned to the system for further use.

If the lubricating oil stock was produced from a mixed base crude, i. e. crude containing both asphalt and wax, it was treated for wax removal subsequent to the deasphaltizing step. This was accomplished by evaporative refrigeration, that is, the pressure on the solution was released and a portion of the solvent was evaporated by the release in pressure which effected chilling of the oil and precipitation of the wax from the propane solution. By reducing the pressure to substantially atmospheric, the temperature of the solution was reduced to approximately —40° F. The precipitated wax was separated from the oil and from the residual solvent by settling, filtration, or centrifuging. The wax-free solution was heated to evaporate the solvent and thus to produce a lubricating oil free from both asphalt and wax.

As a particular feature of the invention, the

use of such hydrocarbon solvents which are volatile at atmospheric temperature and pressure was disclosed to precipitate the asphalt. Such hydrocarbon solvents include propane, iso-butane, ethane, methane or mixtures thereof and are obtainable by rectification of casinghead gasoline by the so-called stabilizing method now conventional in the natural gasoline industry. They comprise the overhead gaseous fractions of the stabilizing process. The gaseous fractions are liquefied by compression and cooling in the conventional manner and are drawn off into pressure chambers where they are maintained in the liquid state until they are used. A typical analysis of such a fraction is 6.72% ethane, 72.20% propane, 19.19% iso-butane and 1.17% normal butane. The necessary pressure to maintain this fraction in a liquid state at approximately 75° F., is about 125 lbs. per sq. in. gauge. In the present invention, I intend to include the use of the foregoing liquefied normally gaseous hydrocarbon solvents.

In the foregoing process, the precipitated asphalt separated from the pressure precipitator comprised a slurry of asphalt and propane from which the latter was separated by distillation to leave a substantially pure asphalt or bitumen. This type of asphalt seriously handicaps the efficient operation of the process due to the fact that it must be heated to a fluid consistency before it can be easily pumped and handled.

In my co-pending application Serial No. 659,855, filed March 6th, 1933 now U. S. Patent 2,010,008, I disclosed a process for the separation of asphalt or asphalt and wax wherein the asphalt was separated as a liquid fraction in the first stage of the process by controlling the volumetric ratio of propane to oil in the manner as will be hereinafter described. This retained a quantity of asphalt in the oil solvent solution. The oil solvent solution was then chilled to precipitate wax and also the remaining asphalt which were separated from the oil solvent solution by settling.

By the present invention I propose to separate the asphalt present in the residuum from the oil in a plurality of stages. In the first stage of the process, the oil or residuum is commingled with a solvent in such ratio as to separate the asphalt as a liquid fraction. This is accomplished by providing a low volumetric ratio of propane to oil. If the ratio of solvent to oil is high, the asphalt is separated as a granular solid or as a substantially pure bitumen containing propane. On the other hand, if this ratio is low the asphalt may

be separated from the oil solvent solution as a liquid fraction. By referring to the asphalt as a liquid fraction, it will be understood that the asphalt separated in the decanter when the residuum containing asphalt is mixed with solvent comprises a substantially homogeneous solution of asphalt, oil and propane which is liquid at atmospheric temperature. It comprises a liquid fraction as distinguished from a slurry of asphalt and propane or a heterogeneous mixture of asphalt and propane containing oil from which the asphalt may be separated from the mixture by simple decantation or filtration.

The amount of propane mixed with the oil will depend to a large extent on the character of the crude or residuum treated. Also the amount of asphalt recovered in this stage will depend upon the propane-oil ratio. For example, a treatment on Poso Creek residuum topped to an on-stream viscosity of 67 seconds Saybolt universal at 100° F., the minimum amount of propane that can be used to effect a separation of phases will exceed approximately 1½ volumes of propane to one volume of oil. On a McKittrick residuum, a separation of phases can be obtained when the volumetric ratio exceeds 0.6 volume of solvent to one volume of oil. A further increase in the volumetric ratio of the respective oils indicates a steady decrease in percentage recovery of the lubricating oil, while the character of the oil is increasingly better as to color. The amount of asphalt recovered will also increase with an increase in the propane to oil ratio. However, the character of the asphalt recovered varies with variation of this ratio. In general, with low volumetric ratios and high percentage of oil recovered, the asphalt separated by stratification is a liquid asphalt. When free of solvent it has a low melting point and a high penetration. By increasing the volumetric ratio, the character of the asphalt stratified and recovered passes from the liquid stage to a solid asphalt or a substantially pure bitumen in finely divided form. The penetration will correspondingly become lower and the melting point higher as the volumetric ratio is increased. In other words, it appears that there is a critical volumetric ratio below which asphalt may be separated from the oil as a liquid fraction and above which the asphalt comprises a granular solid or substantially pure bitumen. In general, the volumetric ratio of 6 or less of propane to one of oil will result in the separation of the asphalt as a liquid fraction, whereas a ratio above this will cause the asphalt to be separated as a solid. I do not wish to be limited to this exact ratio since the upper limit of volumetric ratio for the separation of asphalt as a liquid fraction will depend entirely upon the character of the residuum treated and the degree to which it is topped. With certain stocks, the upper limit of volumetric ratio will be less than 6 to 1, particularly in cases where the asphaltic content of the residuum is high. On a Poso Creek residuum topped to an on-stream viscosity of 67 seconds Saybolt universal at 100° F., the separation of asphalt as a liquid fraction may be effected at a volumetric ratio of 6 to 1 or less. However, I may state that liquid asphalt may be separated from any asphaltic oil at a ratio within the range of approximately 0.6 to 6 volumes of propane to one volume of the oil.

When the process of the first stage is operated to effect removal of asphalt as a liquid fraction, the oil solvent solution is dark and its viscosity is

relatively high which indicates that a substantial amount of asphalt remains in solution. This oil solution is treated in the second stage of the process forming the subject of my invention. I have discovered that when the propane solution of the first stage is mixed with additional propane at the same or at a lower temperature, additional precipitation of asphalt is effected. In most cases, the second precipitate of asphalt will settle as a finely divided material or asphaltic slurry of bitumen and propane. The amount of asphalt separated in the second stage will depend upon the amount of asphalt removed in the first stage which will, of course, depend upon the volumetric ratio of propane to oil employed in the first stage. The amount of asphalt separated in the second stage will also depend upon the volumetric ratio of propane to oil employed in the second stage. In general, this amount will comprise from 2 to 4% of additional asphalt based on the residuum entering the process. This additional amount may be removed by settling or filtration. The propane-oil solution may then be chilled to a temperature between 40° F. and -40° F. to effect a still further precipitation of asphalt or to effect a simultaneous precipitation of asphalt and wax where the oil treated contains wax. If desired, the temperature may be reduced to the cloud point of the wax to separate pseudo asphaltic bodies prior to carrying out the dewaxing operation.

With the above discussion in mind, it will be perceived that it is an object of my invention to separate asphalt from asphalt containing oil by means of a liquefied normally gaseous hydrocarbon solvent under pressure sufficient to maintain the solvent in a liquid state and in an amount sufficient to separate the contained asphalt as a liquid fraction and then adding a further quantity of solvent to the oil solvent solution and separating a further quantity of asphalt at the same or at a lower temperature than the temperature employed in the first stage or a portion may be removed at the same temperature after the addition of further quantities of solvent and the remainder removed at a lower temperature. A particular object of my invention resides in the use of liquid propane as a preferred solvent for accomplishing the above results.

Another object of my invention resides in effecting separation of asphalt from an asphalt and wax containing oil by means of a solvent such as propane in an amount sufficient to cause stratification of two liquid layers, one containing the bulk of oil, propane and wax together with a small amount of unprecipitated asphalt and the other layer containing asphalt and propane together with a small amount of oil, in separating these two liquid layers, in adding a further quantity of propane to the solution of oil and propane containing wax and unseparated asphalt to precipitate said asphalt, in separating the precipitated asphalt from the oil, solvent and wax, in chilling the oil solvent solution containing wax to precipitate the wax, in separating the precipitated wax from the oil solvent solution and in then separating the residual solvent from the oil to produce a lubricating oil substantially free of asphalt and wax.

It is another object of the invention to accomplish chilling of the oil solvent solution by releasing the pressure to evaporate a portion of the solvent.

Other objects and advantages of my invention will be apparent from the following description of my invention taken from the drawing which represents a schematic arrangement for carrying out my invention.

Referring to the drawing, an asphalt containing oil or residuum or an asphalt and wax containing oil is taken from tank 1 and is passed into line 2 by pump 3 where it meets liquid propane coming from propane storage tank 9 via line 10, pump 11 and line 12 controlled by valve 13. The propane and residuum is passed through turbulence or mixing coil 4 and then into decanter or asphalt precipitator 5. The amount of propane introduced into residuum will depend upon whether it is desired to remove the asphalt at the bottom of decanter 5 as a slurry of asphalt and propane, i. e. as a mixture of substantially pure bitumen and propane or as a liquid fraction of asphalt and propane containing some oil. In the preferred operation, it is desirable to separate the asphalt in decanter 5 as a liquid fraction in which case the volumetric ratio of propane to oil employed will be within a range of 0.6 to 6 of propane to one volume of oil, depending upon the character of the oil or residuum treated and the degree to which it was topped. Volumetric ratios higher than those specified will effect precipitation and settling of the asphalt as a slurry of substantially pure bitumen and propane. The asphalt settling to the bottom of decanter 5 is withdrawn by means of pump 6 and line 7 controlled by valve 8 to further treatment as will be hereinafter described.

The clear overflow from decanter 5 consisting of liquid propane and the bulk of the oil is passed into line 14 by means of pump 15 where it meets a stream of liquid propane passed from storage tank 9, line 10 and pump 11 into line 12' controlled by valve 13'. The mixture is then passed into turbulence coil 16 and then into decanter or asphalt precipitator 17 provided with scrapers or agitating paddles 18 operated by belt 19 from any suitable source of power not shown. Decanters 5 and 17 and propane storage tank 9 are maintained at substantially the same pressure by means of equilibrium lines 23 controlled by valves 24 and 24'. This pressure should be sufficient to maintain the solvent in the liquid stage at ordinary temperatures of approximately 75° F. For the solvent given above, that is, propane, this pressure is about 125 to 175 lbs. per sq. in. gauge. If desired, the pressure in decanter 17 may be maintained lower than that in decanter 5 so that a lower temperature may be provided in decanter 17. For example, the temperature in decanter 17 may be reduced to approximately 40° F. to -40° F. depending upon whether the oil contains wax or not. If the oil is substantially free from wax, the temperature may be reduced to approximately 0° F. to -40° F. If the oil contains wax, it is preferable to reduce the temperature to not substantially below that temperature at which wax begins to precipitate. This temperature is approximately 35° F. to 45° F. The temperature reduction in decanter 17 may be effected by closing valve 24' and regulating valve 122 on line 123 which connects to line 71 and the compressor 54. The wax may then be separated in the manner hereinafter described.

The amount of propane introduced into the solution of oil and propane removed from decanter 5 will depend upon the amount of propane already present in the solution and also on the

amount of unseparated asphalt from the first stage. As an example, Santa Fe Springs long residuum topped to approximately 100 viscosity (Saybolt universal at 100° F.) on the overhead stream was extracted in the first stage with three volumes of propane to give a yield of 23% of recovered asphalt based on the residuum which appears as a liquid phase containing approximately 30% propane when equilibrium is reached between three volumes of propane and the residuum under pressure. The clear propane solution is decanted and mixed with 4 additional volumes of propane also at atmospheric temperature and allowed to settle. Approximately 2% to 4% of additional asphalt based on the residuum precipitated and settled to the bottom of the second decanter 17. This asphalt was recovered as a slurry of finely divided substantially pure bitumen and propane at the bottom of decanter 17. Scrapers or vanes 18 prevent the asphalt from adhering to the walls of the decanter and aid in passing the asphalt slurry to a screw conveyor 25 driven by motor 26. The asphalt slurry is passed into line 27 to pump 28 which forces it through valve 29 into lines 30 and 31 to further treatment as will be described hereinafter.

The asphalt settling to the bottom of decanters 5 or 17 as described above may be separately treated for removal of propane or may be treated in admixture. If it is desired to separately treat the asphalt from decanter 5, it is withdrawn from the bottom of the decanter by means of pump 6 and line 7 controlled by valve 8 and passed into lines 30 and 31 where, if desired, it is mixed with a preheated fluxing oil coming from line 40 which is obtained from storage tank 33, pumped by pump 34 through line 35 to heater 36 where it is preheated and is then passed through line 37 into line 38 controlled by valve 39 and thence into line 40 controlled by valve 41 and introduced into line 31 controlled by valve 32.

The mixture of preheated fluxing oil and asphalt removed from decanter 5 containing propane is passed through valve 32 and heating coil 42 where the mixture is heated to a sufficiently high temperature to flux the asphalt and is then passed through pressure reduction valve 44 on line 43 into evaporator 45 which is operated at a lower pressure. If the fluxing oil has been preheated to a sufficiently high temperature to flux the asphalt in line 31, heater 42 may be omitted and the mixture flashed through valve 44 into evaporator 45. Steam superheated in coil 46 is introduced into 45 to supply additional heat and to reduce the mixture to proper specification generally, only as regards flash and fire points. The overhead from evaporator 45 passing through mist extractor 47 is sent through line 48 to cooler 49 and then to separator 50. The uncondensed propane from separator 50 is sent through line 51 controlled by valve 52 to line 53 to the suction of compressor 54 where its pressure is raised to that in the high pressure system and is then sent to cooler 55 where it is liquefied and runs down into propane storage tank 9. Any condensed light oil is withdrawn from separator 50 through line 56 and condensed water is withdrawn through line 57. The asphalt is taken from the bottom of evaporator 45 and sent through line 58 controlled by valve 59 to storage tank 60.

The asphalt slurry settling to the bottom of decanter 17 may likewise be treated in accordance with the method described above for treat-

ing the asphalt recovered from decanter 5. If desired, the preheated fluxing oil may be introduced directly into the outlet 124 of decanter 17 in which case the asphalt slurry would be 5 sufficiently fluid to be pumped without the aid of the screw conveyor 25; or by closing valve 41 and opening valve 126 on line 25 the hot fluxing oil may be introduced directly into the outlet of the screw conveyor. Other possibilities of the hot 10 fluxing oil introduction into the asphalt slurry will be understood by those skilled in the art. If desired, the asphalt from decanter 5 may be mixed with that of decanter 17 and treated in admixture in the evaporator 45.

15 If it is desired to recover the asphalt in either decanter 5 or 17 in substantially pure form, i. e. without cutting back with a fluxing oil of lower viscosity, a small amount of oil passing through line 40 may be introduced through line 31 to 20 start the process and the valve 41 is closed. Then a portion of the asphalt recovered in the evaporator 45 may be continuously circulated via line 120 controlled by valve 121 and pump 122 through 25 a heater 123 and line 124 into line 31 to supply heat for fluxing and evaporation of residual propane in the precipitated asphalt. Heater 42 may be omitted. The introduction of hot fluxing oil into the asphalt recovered from the bottom of decanter 5 is not entirely necessary since this 30 asphalt is substantially liquid and can be readily passed or pumped through the lines connecting decanter 5 with evaporator 45. However, it is preferable to commingle the asphalt settling to the bottom of decanter 17 with hot fluxing oil 35 since this asphalt is heavy and cannot be efficiently handled.

The overflow from decanter 17 consisting of propane and deasphaltized lubricating oil stock is sent through line 61 by pump 62 and then 40 through line 63 controlled by valve 64 to acid treatment and neutralization with alkali in accordance with the method described in my aforementioned co-pending application Serial No. 466,189. However, if the residuum from which 45 the lubricating oil is produced also contains wax, the wax would be dissolved in the overflow from decanter 17 in which case I prefer to close valve 64 and pass the solution into line 65 controlled by pressure reduction valve 66 into low pressure 50 chilling column or evaporator 67. In column 67, sufficient propane vaporizes to reduce the temperature of the remaining material to a predetermined dewaxing temperature which causes wax to precipitate from solution. The desired 55 dewaxing temperature is obtained by controlling the pressure in column 67 by the proper operation of valve 69 on line 68 and compressor 54 which is connected to the evaporator by lines 69, 78, 71, and 53. The pressure to be maintained in column 67 will be generally about 6 lbs. gauge which corresponds to a temperature of approximately 60 -40° F.

As the propane solution passes through valve 66, its pressure is reduced so that a portion of the propane evaporates in column 67 and the 65 vapors pass out of the top through line 68 controlled by valve 68, then through lines 70 and 71 into line 53 and compressor 54 where the vapors are liquefied, cooled in 55 and passed to propane storage tank 9.

The chilled oil dissolved in the propane carrying the precipitated wax is removed from the evaporator or chilling column 67 through line 72 controlled by valve 73 by pump 74, which 70 forces it into the vapor-tight wax separator or

settler 75. In order to prevent ebullition or boiling in the wax separator during the wax settling operation, pressure is imposed upon the solution of oil. This is accomplished by maintaining pressure within the separator by pump 5 14. As the chilled mass in the wax separator remains in a non-ebullient state, the wax settles out and is collected by vanes 76 operated by belt 77 connected to a suitable source of power not shown. The wax-free oil dissolved in propane is 10 withdrawn from the separator 75 and pumped by pump 78 through lines 79 and valve 80 into heater 81 provided with mist extractor 82 where the propane present is vaporized by the aid of steam circulated through the closed steam coil 15 83. The vaporized propane passes out of the heater through line 84 controlled by valve 85, cooled in cooler 86 and then passes through lines 87, 70, 11, and 53 to compressor 54, cooler 55 into storage tank 9. The dewaxed propane-free oil passes from heater 81 by means of line 20 88 controlled by valve 89, through heat exchanger 91, line 92 into tank 93.

The precipitated wax slurry containing propane settling at the bottom of the wax separator 25 75 is removed from the separator through line 94 and is passed through heat exchanger 91 where it extracts heat from the dewaxed oil from the heater 81. The wax slurry is then pumped by pump 95 into line 96 where it is mixed with a 30 hot fluxing oil coming from line 97 controlled by valve 98. This oil may comprise a portion of the fluxing oil passed from tank 33, heated in heater 36 and by-passed into line 97. The mixture of hot fluxing oil and wax slurry is then 35 introduced into line 99, heater 100 and then passed through line 101 into separator 102. Vaporized propane is passed to propane storage tank 9 via line 103 controlled by valve 104, cooler 105, lines 106, 71, and 53, compressor 54 and cooler 40 55. The mixture of propane-free fluxing oil and wax comprising a fuel oil is withdrawn from separator 102 through line 107 and pumped by pump 108 into line 109 controlled by valve 110 45 into storage tank 111. If desired, a portion of 50 this mixture may be by-passed and sent through line 112 controlled by valve 113 to pump 114 which forces it through heater 115 into line 116 and then into line 99 where it meets further quantities of wax slurry from settler 75. 55

If it is desired to recover the wax in settler 75 as a crude petrolatum which may then be purified according to methods now conventional, the fluxing material may comprise an initial amount of petrolatum preheated to a temperature of approximately 350° F. and introduced 60 into line 99 which is mixed with the wax slurry in the proportions of two volumes of preheated petrolatum to one volume of wax slurry. The mixture is then passed into separator 102 where propane is vaporized. Heater 100 may be omitted. The crude petrolatum is withdrawn from separator 102 at a temperature of approximately 200° F. which is sufficiently high above the melting point of the petrolatum to permit 65 efficient pumping and handling and is then passed through line 107 and pump 108, one volume of the material passing into tank 111 and the other two volumes are recirculated into line 99 via line 112 and pump 114 which forces the material 70 through heater 115 where the temperature is again raised to 350° F. and passed into lines 116 and 99. The cyclic circulation through line 112, heater 115, line 116 into line 99 is carried 75 on continuously.

If desired, the initial amount of preheated petrolatum introduced into line 99 may be substituted by an initial volume of preheated petroleum residuum which is circulated through the apparatus in the manner described above, one volume being withdrawn into tank 111 while the remainder is recirculated into the wax slurry coming from separator 75. After a number of such circulations, the material passing into line 107 will be sufficiently free from petroleum residuum and will comprise a crude petrolatum. Consequently, the material collecting in tank 111 and the portion recirculated through heater 115 will also comprise a crude petrolatum.

If it is desired to convert the wax into fuel oil, it is preferable to mix the wax slurry coming from settler 75 with a cracked residuum continuously introduced into line 99 via line 97, said cracked residuum possessing a pour point depressant. If the cracked residuum is at a sufficiently high temperature, say about 500° F., heater 100 may be omitted or by-passed and the mixture passed directly into separator 102 to permit vaporization of propane. The mixture from separator 102 comprising a fuel oil is then passed to storage tank 111 or a portion thereof may be recirculated into line 99 via heater 115.

If desired, the overflow from decanter 5 may be acid and alkali treated prior to dewaxing in the manner described in my aforementioned co-pending application.

It is to be understood that the above is merely illustrative of preferred embodiments of my invention of which many variations may be made by those skilled in the art without departing from the spirit thereof.

I claim:

1. A process for separating the diluent from solidified impurities removed from oils by the aid of such diluent which comprises mixing the solidified impurities containing the diluent with a preheated oil and evaporating the diluent from the mixture.

2. A process for separating the diluent from solidified impurities removed from oils by the aid of a light liquid hydrocarbon which comprises mixing the solidified impurities containing the diluent with a preheated oil and fluxing the same and evaporating the diluent from the mixture.

3. A process for treating oils which comprises mixing the oil with a liquid capable of precipitating impurities solidifiable at ordinary temperatures from the oil, separating said impurities containing a portion of said liquid from the oil, mixing said separated impurities and liquid with a preheated oil and evaporating the liquid from the mixture.

4. A process as in claim 3 in which the liquid is normally gaseous.

5. A process as in claim 3 in which the liquid is a normally gaseous hydrocarbon.

6. A process as in claim 3 in which the liquid is propane.

7. A process for the separation of asphalt from oils containing the same which comprises mixing the oil with a liquid capable of precipitating the asphalt from the oil, removing the precipitated asphalt containing a small amount of said liquid, mixing said separated asphalt and diluent with heated oil and fluxing the asphalt and evaporating the liquid from the mixture.

8. A process for the separation of asphalt from oils containing the same which comprises mixing the oil with an asphalt precipitating liquid, mix-

ing the precipitated asphalt containing a small amount of said liquid with an oil heated to a sufficiently elevated temperature to flux the asphalt and removing evaporated liquid from the fluxed asphalt.

9. A process for the separation of asphalt from oils containing the same which comprises mixing the oil with an asphalt precipitating liquid, separating the precipitated asphalt containing a small amount of said liquid from the remaining oil and liquid, commingling the separated asphalt and liquid with hot asphalt and evaporating the liquid from the mixture.

10. A process for the separation of asphalt from oils containing the same which comprises mixing the oil with an asphalt precipitating liquid, separating the precipitated asphalt containing a small amount of said liquid from the remaining oil and liquid, fluxing the separated asphalt and liquid with oil, evaporating said liquid from the mixture and recirculating preheated asphalt to said asphalt containing asphalt precipitating liquid separated from oil containing asphalt.

11. A process for the separation of wax from oils containing the same which comprises mixing the oil with a diluent, chilling the mixture to precipitate wax and separating the precipitated wax containing a small amount of diluent from the oil and remaining diluent, mixing said separated wax and diluent with preheated oil and evaporating the diluent from the mixture.

12. A process for removing diluent from wax slurry separated from oils in the presence of diluent which comprises mixing the separated wax slurry containing diluent with a hot oil to flux the wax and evaporate diluent and separating the diluent from the mixture.

13. A process for treating wax slurry containing diluent which comprises commingling the wax slurry with hot wax and evaporating diluent from the mixture.

14. A process for treating wax slurry containing diluent which comprises commingling the wax slurry in the preheated wax and evaporating diluent from the mixture and recirculating a portion of said mixture from which diluent has been evaporated for admixture with further quantities of wax slurry.

15. A process as in claim 13 in which the wax mixed with the wax slurry is petrolatum.

16. A process as in claim 14 in which the preheated wax initially mixed with the wax slurry is petrolatum.

17. A process for treating wax slurry which comprises mixing the wax slurry with preheated petroleum residuum at an elevated temperature and circulating a portion of the mixture for admixture with further quantities of wax slurry.

18. A process as in claim 17 in which the preheated petroleum residuum is a cracked residuum.

19. A process for treating wax slurry containing a small quantity of diluent which comprises fluxing the wax slurry with hot oil at a temperature sufficient to evaporate the diluent, passing the mixture into a vaporizer wherein the diluent is removed from the mixture, withdrawing the fluxed mixture from the vaporizer, heating a portion of said withdrawn mixture and mixing said heated portion with further amounts of wax slurry containing diluent.

20. A process as in claim 19 in which the hot oil is petrolatum.

ULRIC B. BRAY.
